(57) **CLAIM**

The ornamental design for a towel, as shown and described.

DESCRIPTION

FIG. 1 is a front-top-right perspective view of a towel showing my new design;

FIG. 2 is a rear-bottom-right perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is an top plan view thereof; and,

FIG. 8 is an bottom plan view thereof.

The broken lines showing stranded ends of the towel in FIGS. 1 through 6 and FIG. 8 show portions of the towel that form no part of the claimed design.

1 Claim, 8 Drawing Sheets
